UNITED STATES PATENT OFFICE.

JOSEPH LISTER, DECEASED, LATE OF CHICAGO, ILLINOIS; BY EDWIN LISTER, EXECUTOR, OF CHICAGO, ILLINOIS.

RENDERING PROCESS.

Application filed June 9, 1917, Serial No. 173,734. Renewed February 3, 1923.

To all whom it may concern:

Be it known that JOSEPH LISTER, recently deceased, a citizen of the United States, residing at Chicago, in the county of Cook and State of Illinois, did invent certain new and useful Improvements in Rendering Processes, of which the following is a specification.

This invention is concerned with certain novel processes which are adapted to be carried out conveniently by the use of a tank and connections, which tank will be illustrated and described, together with the novel process of rendering tallow which may be carried out thereby.

To illustrate the aforesaid invention, three sheets of drawings are annexed hereto, in which the same reference characters are used to designate identical parts in all the figures, of which,—

Fig. 1 is an end elevation of the tank;

Fig. 2 is a side elevation of the same; and

Fig. 3 is a longitudinal central vertical section.

In carrying out the aforesaid invention, a cylindrical tank 15 may be employed, which is provided with heads 16 and 17, each of said heads having suitably secured thereto the trunnions 18 and 19, which trunnions are preferably hollow and constructed with the stuffing-box caps 20 and 21, which are adjusted to compress the packing, not shown, about the stationary pipes 22 and 23 by the set screws 24 passing through the caps 20 and 21 and threaded into the ends of the trunnions 18 and 19. The inner end of the trunnion 19 opens into the short pipe 25, rigidly secured in the tank, in any desired manner, as by being screwed into the end of the plate 26 secured on the inner end of the head or end 17. A radially extending pipe 27 is connected to the pipe 25, as by the elbow 28, and a longitudinally extending pipe 29 at the periphery is connected to the pipe 27 by the elbow 30. As a convenient means of holding the pipe 29 from movement, I secure it by the loops 31 passed around it and extended through the wall of the tank 15. This projecting loop serves to show at all times the position of the pipe 29. The pipe 29 terminates at substantially the center of the length of the tank, and is connected by an elbow 32 and a T 33 with an elongated

perforated pipe 1, which is also preferably secured from movement by the loops 35 surrounding it and passed through the wall of the tank. By the connections shown, it will be obvious that a fluid can be passed into the tank through the pipes 23, 25, 27, 29 and 1, or, by a reverse movement, withdrawn therefrom. The pipe 23 has a vertical extension 36, in which is located a cock 37 connected to the test or discharge pipe 12. The upper end of the pipe 36, or a continuation thereof, is connected to the header pipe 38, which pipe has connected thereto by elbows or T's, as may be required, the steam supply pipe 3, the grease discharge pipe 4, the glue discharge pipe 5, the hot-water supply pipe 6, and the gas discharge pipe 14. All these pipes are supplied with stop cocks, as shown, and it will be understood that the hot-water pipe 6 is connected to a supply of hot water; the glue discharge pipe 5 is adapted to discharge into some suitable receptacle for the further treatment of the glue; the grease discharge pipe 4 likewise discharges into some receptacle for the grease; the steam supply pipe 3 is connected to a supply of live steam, and the gas discharge pipe 14 terminates at some point, preferably outside of the plant, where ammonia gas, if it is not preserved, can be discharged without inconvenience. In the pipe 14 below the valve, I place the pressure gauge 39, which, when the cock 40 in the pipe 36 is open, will show the pressure in the tank. The tank 15 is provided with the customary manhole 11, which may be closed by the customary solid cover, or by a special perforated cover 41, indicated somewhat diagrammatically in Fig. 2.

The other end of the tank is provided with a short pipe 42, like the pipe 25, which is suitably connected to the radial pipe 43, which in turn is suitably connected to the short perforated pipe 2, and it will be obvious that the pipe 2 can be used to admit or take out fluids from the tank 15 in the same general manner as where the pipe 1 is employed. The outer end of the stationary pipe 22 is suitably connected to the vertical pipe 44, which is connected to the header pipe 46, which in turn is suitably connected to the hot-water pipe 7, the cold-water supply pipe 8, the steam supply pipe 9, and the compressed-air supply pipe 10, each of

these pipes 7, 8, 9 and 10 being provided above the header 46 with the shut-off valve and it will be understood that the pipe 7 can be connected to a supply of hot water, or sometimes to a supply of "liquor" water; the cold-water supply pipe 8 is connected to a supply of cold water; the steam supply pipe 9 to a supply of live steam; and the air pipe 10 is connected to a supply of compressed air.

As seen in Fig. 3, the interior of the tank may be provided with the inwardly projecting plates 47, to lift the contents of the tank as it is rotated, it being provided with the 15 spur gear wheel 48 secured on the trunnion 19, which gear wheel is driven by the spur gear pinion 49 secured on the shaft 50, journaled in suitable bearings on the framework 51, and having the belt pulley 52 on 20 the outer end thereof, by which power is applied to the drum to rotate the same. It will be noted that the pipe 2 is diametrically opposite to the pipe 1, and that the relative positions of the pipes 1 and 2, whether at 25 the top, bottom or side of the tank, can always be ascertained by reference to the loops 31 and 35.

To illustrate how the tank is used in my novel method of rendering tallow, the following description is given. The tank will be partially filled with the material, which includes all classes of tallow, caul, mecca, kidney, flank, and various gristly fat parts from cattle and sheep. If the material is 35 dirty, it may be washed by closing the man-hole 11 with the perforated screen 41, and with the manhole at the top, the valve 8 is opened and the tank filled with cold water, after which it is revolved until it is emptied by the water escaping through the 40 perforated cover of the manhole. This washing process may be repeated two or three times, as often as is necessary to remove blood, salt, and impurities generally. 45 After it is washed, the manhole is turned to the top, and the perforated cover is removed and the solid cover put in place; the valve 3 is opened, with the pipe 1 standing at the bottom, and the live steam is admitted to scald the contents. The pressure is 50 raised to forty pounds, as indicated on the gauge 39, after which the valve 3 is closed. The tank is rotated to bring the pipe 1 to the top, after which the valve 14 is opened, 55 and the accumulated gas and steam blown off, after which the tank is turned to bring the pipe to the bottom, after which the valve 3 is opened, admitting steam until the pressure is raised again to forty pounds. 60 The valve 3 is then closed, and the tank turned to bring the pipe 1 to the top, after which the valve 14 is opened long enough to blow out the gas and allow the pressure to fall to twenty pounds, after which the 65 tank is turned to bring the pipe 1 to the

bottom, in which position the tank is allowed to stay for one-half hour, until the fluid contents are stratified.

The valve 5 is now opened, and the pressure in the tank forces out the glue liquor which occupies the bottom of the tank. The run of the liquor has to be watched, and at the end, when the overlying tallow begins to appear, the valve 5 has to be closed, and the valve 6 is opened, and a certain definite quantity of hot water, enough to half fill the tank, is admitted, after which, with the pipe 1 remaining on the bottom, the valve 3 is opened and steam admitted to raise the pressure to forty pounds. The tank is then turned to bring the pipe 1 to the top, after which the valve 14 is opened, and the gas and steam blown off. The valve 14 is then closed and the tank turned to bring the pipe 1 to the bottom of the tank, after which the valve 3 is opened and steam admitted until the pressure is raised to forty pounds, after which the tank is allowed to remain stationary for three hours with the pressure held at forty pounds. The tank is then turned until the pipe 1 is at the side, and the fat will be floating on the top of the water, which half fills the tank, as previously mentioned. The valve for the pipe 4 is then opened, and the internal pressure forces the tallow off of the top of the water or liquor in the tank, and then the valve is closed. The tank is then turned to bring the pipe 1 to the bottom, after which the valve 3 is opened and steam admitted to raise the pressure to forty pounds. The valve 3 is closed, and the valve or pipe 12 is opened, and the pressure forces all the water out. When the water is all gone, some grease will follow it, and when it appears, the valve 12 must be closed and the valve 4 opened, and the grease discharged through the pipe 4 to a suitable receptacle. The tank is then turned to bring the pipe 2 to the bottom, and the valve 9 is opened, and steam flows through the tank, penetrating through the tankage to pipe 1 for one and a half to two hours, at the end of which time only a dry steam will come from the pipe 14, which is then closed, after which the manhole plate is removed, and the tank is revolved until the tankage contents are discharged therefrom.

While I show a preferred form of tank for carrying out said process and the rendering process is likewise described in its preferred embodiment, it will be understood that different forms of tanks or apparatus may be employed and that the process is capable of some modifications, and that the patent is not to be limited to the exact steps disclosed, but only as may be necessitated by the state of the prior art.

What it is desired to claim as new is:

1. A rendering process which consists of

- (1) treating the stock by the direct action of steam; (2) allowing the stock to settle while kept hot but without dilution; (3) drawing off hot, undiluted glue liquor; (4) treating the stock by the direct action of steam; (5) adding hot water to float the tallow above the residue; and (6) skimming off the tallow.
2. A tank rendering process consisting of (1) cooking the stock in steam and agitating it to free the fats and glutinous materials from the residue; (2) allowing the stock to settle for thirty minutes under twenty pounds steam pressure; (3) drawing off the glue liquor from the bottom of the tank; (4) adding hot water to half fill the tank and float the residue; (5) subjecting it to forty pounds steam pressure for three hours; and (6) skimming off the tallow.
3. A tank rendering process consisting of (1) cooking the stock in steam and agitating it to free the fats and glutinous materials from the residue; (2) allowing the stock to settle for thirty minutes under twenty pounds steam pressure; (3) drawing off the glue liquor from the bottom of the tank; (4) adding hot water to half fill the tank and float the residue; (5) subjecting it to forty pounds steam pressure for three hours; (6) skimming off the tallow; (7) drawing off the water; (8) drawing off the remaining grease; and (9) steaming the residue for one and one-half hours.
4. A rendering process consisting of (1) treating stock by steam under pressure; (2) allowing stock to settle; (3) forcing off undiluted glue liquor from the bottom by pressure on the top of the stock; (4) treating remainder of stock by water and steam under pressure; (5) forcing off the tallow by pressure; (6) driving off water by pressure; and (7) driving off the balance of the tallow by pressure.
5. A novel rendering process which consists in (1) washing the stock; (2) scalding the stock; (3) steaming the stock under pressure; (4) releasing the pressure and discharging the gas; (5) steaming the stock under pressure; (6) reducing the pressure; (7) allowing the stock to stratify; (8) drawing off glue liquor; (9) adding water; (10) steaming the stock under pressure; (11) releasing the pressure and gas; (12) steaming the stock under pressure for three hours; (13) skimming off the tallow by pressure; (14) driving the water off by pressure; and (15) driving off the balance of the tallow by pressure.
6. A tank rendering process for fats and gelatinous materials, which consists of (1) cooking and agitating the stock without the addition of water to free said fats and gelatin from the residuum; (2) allowing the materials to stratify without solidifying; (3) drawing off the glue liquor from the bottom; (4) adding hot water to float the fats above the residue; (5) and skimming off the fats from above the residue and the water.
7. A tank rendering process for fats and gelatinous materials, which consists of (1) cooking and agitating the stock without the addition of water to free said fats and gelatin from the residuum; (2) allowing the materials to stratify without solidifying; (3) drawing off the glue liquor from the bottom; (4) adding hot water to float the fats above the residue; (5) skimming off the fats from above the residue and the water; (6) drawing off the water; and (7) steaming the residue.
8. A tank rendering process for fats and gelatinous materials, which consists of (1) cooking and agitating the stock without the addition of water to free said fats and gelatin from the residuum; (2) allowing the materials to stratify without solidifying; (3) drawing off the glue liquor from the bottom; (4) adding hot water to float the fats above the residue; (5) cooking the remaining contents under pressure; and (6) drawing off the fats from above the residue and water.
9. A tank rendering process which consists in (1) washing the stock in cold water; (2) scalding it with live steam at a pressure of forty pounds; (3) blowing off the steam and gas; (4) scalding it again with live steam at a pressure of forty pounds; (5) blowing off the steam and gas; (6) settling for thirty minutes at twenty pounds of steam pressure; (7) drawing off the glue liquor from the bottom of the tank; (8) adding hot water to half fill the tank; (9) admitting steam to raise the pressure to forty pounds; (10) blowing off the steam and gas; (11) admitting steam to raise the pressure to forty pounds and holding it at that pressure for three hours; (12) skimming off the tallow; (13) admitting steam to raise the pressure to forty pounds and force out the water; (14) drawing off the remaining grease; and (15) steaming the residue for one and one-half hours.

EDWIN LISTER,
Executor of Joseph Lister, Deceased.
